UNITED STATES PATENT OFFICE

EDWARD CRAIG AND WILLIAM O. COOPER, OF BREA, CALIFORNIA

DRILL PIPE PROTECTOR

Application filed April 5, 1930. Serial No. 441,842.

This invention relates to a device for use on well drilling apparatus and relates more particularly to a protective guide and bearing device for rotary drill pipe.

5 It is a general object of the invention to provide a device that is adapted to be applied to a string of rotary drill pipe, or the like, to prevent the drill pipe from becoming excessively worn due to engagement with the walls of the 10 well bore or the well casing and to prevent the casing from becoming worn due to the swinging or eccentric motion of the drilling string and which operates to guide the string of 15 drill pipe so that a drilling tool at its lower end will drill a straight hole.

It is an object of the invention to provide a simple, practical, and effective protector or bearing device for rotary drill pipe.

20 It is another object of the invention to provide a device of the character mentioned that may be easily and quickly applied to the drill pipe and which embodies novel and improved means for tightly setting or securing it on the drill pipe.

25 It is another object of the invention to provide a drill pipe protector that may be mounted on the drill pipe to operate within the casing set in the well or to operate in the open well bore below the lower end of the set 30 casing and that may be mounted on the drill pipe, drill pipe couplings, drill collars, or any other part of the drilling string.

35 It is a further object of the invention to provide a drill pipe protector of the character mentioned that embodies rotatable rollers for engaging the casing or well bore that are mounted so that they are not subjected to becoming muddled up or crushed or made inoperative through use.

40 Other objects and features of our invention will be best and more fully understood from the following detailed description of typical forms and applications of our invention, throughout which description reference 45 is had to the accompanying drawings, in which.

50 Fig. 1 is a view illustrating a portion of a string of drill pipe within a well bore showing devices provided by this invention mounted on the string. Fig. 2 is a trans-

verse sectional view through a drill pipe within a well casing illustrating one form of protector provided by this invention mounted on the drill pipe. Fig. 3 is an enlarged 55 vertical detailed sectional view taken as indicated by line 3-3 on Fig. 2. Fig. 4 is an enlarged vertical detailed sectional view taken as indicated by line 4-4 on Fig. 2. Fig. 5 is an enlarged vertical detailed sectional view taken substantially as indicated 60 by line 5-5 on Fig. 2. Fig. 6 is an enlarged vertical detailed sectional view taken as indicated by line 6-6 on Fig. 2. Fig. 7 is a transverse sectional view of a drill pipe with 65 in a well casing illustrating another form of the invention applied to the drill pipe. Fig. 8 is a vertical detailed sectional view taken as indicated by line 8-8 on Fig. 7. Fig. 9 is an enlarged vertical detailed sectional view taken as indicated by line 9-9 on Fig. 7. 70

The device provided by our present invention is adapted to be mounted on an operating or drilling string of drill pipe, or the like, to be operated within a well, and a plurality of devices may be mounted on the drilling string at spaced intervals to operate either in the portion of the well in which casing has been set or in the open well bore below the lower end of the set casing. The 75 protectors may be suitably proportioned for application to the drill pipe, drill collars, drill pipe couplings, etc., of various sizes and for use either in well casing or an open well bore. In Fig. 1 of the drawings we have 80 illustrated two of the protectors mounted on adjoining lengths of drill pipe P extending through well casing C and have illustrated a protector mounted on a drill collar F for operation within the open well bore W below 85 the lower end of the casing C. A typical fishtail type of drilling bit B is shown carried by the drill collar F at the lower end of the string of drill pipe P. Any number 90 of the protectors may be mounted on a string 95 of drill pipe, or the like, at spaced intervals as desired or necessary, and therefore the invention is not to be construed as limited to the particular arrangement of the protectors mounted on successive lengths of 100

drill pipe as illustrated in Fig. 1 of the drawings.

In practice it is sometimes inconvenient and undesirable to arrange the protectors on the drill pipe by sliding them over an end of the pipe. The invention may be embodied in a form which is adapted to be arranged on the drill pipe without being slid over the end of the pipe as well as in a form which may be applied to the pipe by being arranged over and end of the pipe. In Figs. 2 to 6, inclusive, of the drawings we have illustrated a form of the invention which may be mounted on a string of drill pipe, or the like, by being arranged around the pipe without being slid over its end, while in Figs. 7 to 9, inclusive, of the drawings we have illustrated a form of the invention intended to be slid over an end of the pipe into operating position.

The form of the invention illustrated in Figs. 2 to 6, inclusive, of the drawings includes, generally, a cage 10 adapted to be arranged on a drill pipe P, or a drill collar F, or the like, means 11 for setting or locking the cage 10 on the drill pipe, and a plurality of guiding or bearing parts in the form of rollers 12 carried by the cage 10.

The cage 10 is provided to carry the rollers 12 and is in the nature of a substantially annular assembly. The cage 10 includes two spaced rings which we will term upper and lower rings 13 and 14, respectively. The rings 13 and 14 are spaced apart longitudinally or vertically of the drill pipe P, and are connected by circumferentially spaced longitudinal spacer ribs 15. The rings 13 and 14 are proportioned to extend or fit around a drill pipe P, or the like, and their inner sides are formed to effectively seat against or engage the exterior of the pipe. In the particular form of the invention illustrated in Figs. 2 to 6, inclusive, of the drawings the inner sides of each of the rings 13 and 14 are adapted to engage the drill pipe at spaced points. The inner edges of the rings 13 and 14 are provided with alternate depressions and inwardly extending projections 16. The projections 16 of the rings 13 and 14 are in longitudinal or vertical alignment when the cage is in operative position on the drill pipe. The projections 16 may be curved as illustrated in the drawings.

In the form of the invention illustrated in Figs. 2 to 6, inclusive, of the drawings, the cage 10 is adapted to be arranged in operating position on a drill pipe, or the like, without being slid over an end of the pipe. The rings 13 and 14 are longitudinally split at substantially diametrically opposite points so that the cage is divided into two substantially like sections A and D. The rings 13 and 14 are split or divided at points between the spacing ribs 15. Each section may be an integral unit or may be constructed or

built up in other manners as desired. The sections A and D are hinged or pivoted together adjacent one of their lines of division by a pivot pin 17 extending through openings 18 in overlapping parts 20 on the sections. The overlapping parts 20 of the sections A and D are related and fitted together so that the sections are held against relative longitudinal movement. The pin 17 may extend completely through the overlapping parts 20 and may be provided at its opposite ends with heads 21 which positively prevent displacement of the pin. The outer and upper corner of the upper ring 13 may be beveled, while the lower and outer corner of the lower ring 14 may be beveled as illustrated in the drawings.

The means 11 for locking or setting the cage 10 in operating position on the drill pipe is such that the sections A and D of the cage may be swung together around the pipe and locked in position where the cage cannot shift either longitudinally or circumferentially on the pipe. The means 11 includes means for locking or holding the free or outer ends of the sections A and D together and grips or pipe gripping parts 22 for gripping the drill pipe P. In accordance with the form of the invention illustrated in Figs. 2 to 6, inclusive, of the drawings the means for locking the free ends of the sections A and D together is in the form of a wedge means for tightly clamping the sections onto the drill pipe P so that the grips 22 bite into the drill pipe P.

The free or outer ends of the sections A and D of the cage 10 are provided with overlapping portions which extend over one another or overlap when the sections are arranged around the drill pipe P. In the particular case illustrated, the section D is provided with tongues 23 adapted to seat in recesses 24 in the outer end of the section A to overlap portions 25 on the section A. A longitudinally tapered wedge pin 28 is adapted to be arranged or driven through openings 29 in the overlapping tongues 23 and portions 25 to securely clamp the sections onto the drill pipe P. The wedge receiving openings 29 of the section D are preferably made elongated and are positioned and related so that when the wedge pin 28 is driven through them into locking position the sections A and D tightly grip the drill pipe P. The overlapping portions at the free ends of the sections A and D fit together with sufficient clearance to permit the arranging of the wedge pin 28 through the openings 29 and 31. The large end of the wedge pin 28 is provided with a head 33 which, in the particular case shown, may seat against the upper side of the portion 23 of the upper ring 13. The small or reduced end of the pin 28 is adapted to project from the cage 10 and in the case illustrated projects downwardly from the lower ring 14. A washer 34 may be retained on the projecting

lower end of the pin 28 by a suitable key 35 to lock the pin 28 in position.

The grips or gripping parts 22 are provided on the rings 13 and 14 to grip or bite into the drill pipe P when the locking pin 28 is driven into retaining position so that the cage 10 is positively prevented from shifting on the pipe. In this form of the invention a plurality of grips 22 are provided on each of the rings 13 and 14. The grips 22 are set in recesses or sockets 23^a in the inner sides of the rings 13 and 14. The grips 22 may be arranged in the projections 16 on the inner sides of the rings and may be provided with sharpened ends which project radially inward from the rings 13 and 14 to grip the pipe P. The grips 22 may be formed of hard metal and may be fitted tightly in the sockets 23^a. When the wedge pin 28 is driven through the openings in the overlapping portions of the rings 13 and 14 the pointed projecting ends of the grips 22 bite into the drill pipe P to securely hold the cage 10 against movement on the drill pipe P. In practice small notches or sockets may be punched or otherwise formed in the wall of the drill pipe to receive the grips.

The bearing rollers 12 are rotatably carried by the cage 10 and are provided for engaging the interior of the casing C or the formation of the well bore W to guide and protect the drill pipe and to prevent excessive wearing of the casing C. The rollers 12 are rotatably mounted between the rings 13 and 14 to rotate about vertical axes parallel to the axis of the drilling string. The rollers 12 may be formed of rubber, rubber composition, or any other suitable material, and their exteriors may be regular and parallel to their axes of rotation. The rollers 12 may be equally spaced about the axis of the cage and the upper and lower ends of the rollers 12 may be rounded as illustrated in the drawings. The rollers 12 are proportioned and mounted so that they project outwardly beyond the outer sides of the rings 13 and 14 so that they are adapted to engage the casing C or the wall of the well bore W. The inner sides of the rollers 12 are spaced a short distance from the exterior of the drill pipe P or other member on which the cage 10 is mounted.

The rollers 12 are rotatably mounted on vertical pins or shafts 36 extending between the rings 13 and 14. In the form of the invention illustrated in Figs. 1 to 6, inclusive, of the drawings the rollers 12 are provided with bushings 37 for operation on the shafts 36. In the event that the rollers 12 are formed of rubber, the bodies of the rollers may be directly molded or vulcanized onto the bushings 37. The pins 36 are preferably carried by the rings 13 and 14 at points outwardly of or opposite the projections 16. In the case illustrated a roller 12 is mounted

in alignment with each of the projections 16. The lower ends of the pins 36 seat into sockets 40 in the lower ring 14, while the upper ends of the pins extend into openings 41 in the upper ring 13. The openings 41 may extend completely through the ring 13 so that pins 36 may be inserted through them into operating positions. A plug 42 may be provided in each of the openings 41 at the ends of the pins 36 to close the openings. The outer edges of the openings 41 may be peened over as illustrated at 43 in Fig. 3 of the drawings to retain the plugs 42 and pins 36 in position. Longitudinal openings 44 may extend from the lower end of the lower ring 14 to the sockets 40. The openings 44 are of less diameter than the sockets 40 and are adapted to receive a punch or drift for driving the pins 36 through the rollers 12 and openings 41 when it is desired to remove the rollers for replacement, etc.

In Figs. 7 to 9, inclusive, of the drawings we have illustrated a simple form of the invention adapted to be arranged on the drill pipe P, or the like, by being slid over an end of the pipe. This form of the invention includes a cage 10^a adapted to be applied to the drill pipe P. The cage 10^a may include an upper ring 13^a and a lower ring 14^a. The rings 13^a and 14^a may be connected by circumferentially spaced ribs 15^a. The cage 10^a may be in the nature of an integral structure. The inner sides of the rings 13^a and 14^a may be provided with spaced inwardly extending projections 16^a for engaging the exterior of the pipe P.

Bearing rollers 12^a are rotatably carried by the cage 10^a for engaging the interior of the casing C or the well bore W. The rollers 12^a are rotatably mounted on vertical shafts or pins 50 extending between the rings 13^a and 14^a. The pins 50 may be carried by the rings in the same manner as the pins 36 of the form of the invention just described. The rollers 12^a may be formed of rubber, or the like, and their exteriors may be smooth and parallel to their axes of rotation. In this form of the invention the rollers 12^a may be rotatably mounted directly on the pins 50.

Means is provided for securely setting or locking the cage 10^a onto a drill pipe P, or the like. Gripping parts 51 are arranged in openings 52 in the rings 13^a and 14^a to grip the drill pipe P. The gripping parts 51 may be formed of hard metal. The gripping parts 51 are provided with sharpened inner ends to effectively grip the drill pipe P. The openings 52 extend transversely or radially through the rings 13^a and 14^a and the gripping parts 51 may be driven into gripping engagement with the pipe P from the exterior of the rings. In accordance with this form of the invention means is provided for setting or holding the gripping parts 51 in gripping engagement with the pipe. A set

screw 53 is threaded into each of the openings 52 to clamp inwardly against the gripping parts 51. The set screws 53 may be of the socket head type and may be flush with the exterior of the rings 13^a and 14^a or may be countersunk in the openings 52.

It is believed that the operation and utility of the protectors provided by this invention will be readily apparent from the foregoing detailed description. In using the protectors a plurality of the devices may be arranged on the drilling or operating string of drill pipe P, or the like, at spaced points. It will be apparent that there may be any desired or necessary number of protectors arranged on the string at any desired points. It is to be noted that the form of protector illustrated in Figs. 2 to 6, inclusive, of the drawings is particularly easy to apply to a pipe and grips the pipe very securely. It is to be further noted that the rollers 12 are mounted so that lateral thrust or strain received by them will not cause the pins 36 to be bent or distorted or cause the rollers to be crushed. The rollers are mounted so that their inner sides are spaced a short distance from the pipe P so that they are compressed into engagement with the pipe when they are subjected to pressure. It will be further noted that the rollers 12 are mounted so that they are not subjected to becoming muddled up. In the form of the invention illustrated in Figs. 2 to 6, inclusive, of the drawings the device may be readily removed from a drill pipe, or the like, by driving the wedge pin 28 from the sections A and D to free the sections from the drill pipe. The rollers 12 are easily replaced by driving the pins 36 through the openings 41.

40. The form of the invention illustrated in Figs. 7 to 9, inclusive, of the drawings may be removed from the drill pipe by unscrewing the set screws 53 and tapping or otherwise manipulating the cage 10 to release the grips 51 from the pipe.

Having described only typical, preferred forms of our invention, we do not wish to limit ourselves to the specific details set forth, but wish to reserve to ourselves any changes or variations that may appear to those skilled in the art or fall within the scope of the following claims:

Having described our invention, we claim:

55. A device of the character described adapted to be used in connection with a string of drill pipe, including, a cage adapted to be arranged on a length of the drill pipe to surround the pipe, means for securing the cage on the drill pipe, and a yieldable bearing part carried by the cage to have its outer side projecting from the cage and its inner side adjacent the pipe so as to compress against the pipe when distorted.

60. A device for use on a string of drill pipe including, a cage to be arranged around a

length of pipe of the string, means for holding the cage against movement on the pipe, including a gripping part on the cage to bite into the pipe, and a plurality of yielding rollers rotatably carried by the cage and adapted to be compressed against the pipe when distorted.

65. A device for use on a string of drill pipe including, a cage to be arranged around the string, means for holding the cage against movement on the string, including a sharpened gripping part on the cage, and means for forcing the gripping part into the drill pipe, and a rotatable yielding roller on the cage projecting from the cage and adapted to be compressed against the pipe when distorted.

70. A bearing device for a string of drill pipe including, a cage adapted to be arranged on the string including, spaced rings adapted to surround a length of pipe, and rotatable yieldable rollers between the rings, the peripheries of the rollers being adjacent the exterior of the string so as to engage the pipe when the rollers are distorted inwardly.

75. A bearing device for a string of drill pipe including, a cage adapted to be arranged on the drill pipe, the cage including two vertically spaced rings, and a spacer rib connecting the rings, and a plurality of yielding rollers between the rings rotatable about vertical axes, the outer sides of the rollers projecting beyond the rings and the inner sides of the rollers being spaced a short distance from the drill pipe so as to engage the pipe when the rollers are distorted inwardly.

80. A bearing device for a string of drill pipe including, a cage adapted to be arranged on the drill pipe, the cage including two vertically spaced rings, and a spacer rib connecting the rings, a plurality of rubber rollers, and shafts extending between the rings and carrying the rollers for rotation about vertical axes, the outer sides of the rollers projecting beyond the rings and the inner sides of the rollers being spaced a short distance from the drill pipe so as to engage the pipe when the rollers are distorted inwardly.

85. A bearing device for a string of drill pipe including, a cage adapted to be arranged on the drill pipe, the cage including two spaced rings, and ribs rigidly connecting the rings, means for holding the cage against movement on the pipe, and a plurality of circumferentially spaced rubber rollers rotatably mounted between the rings to rotate about axes parallel to the axis of the pipe, the rollers being mounted to project outward beyond the cage and to have their inner portions adjacent the pipe so as to compress against the pipe when distorted.

90. A bearing device for a string of drill pipe including, a cage adapted to be arranged on the drill pipe, the cage including two spaced rings, and ribs rigidly connecting the

5 rings, means for holding the cage against movement on the pipe, a shaft extending between the rings, and a yielding rubber roller rotatable on the shaft and projecting beyond the rings and having its inner portions adjacent the pipe so as to compress against the pipe when distorted by blows against the well wall.

9. A bearing device for a string of drill pipe including, a cage adapted to be arranged on the drill pipe, the cage including two spaced rings, and ribs rigidly connecting the rings, means for holding the cage against movement on the pipe, a removable shaft 15 extending between the rings, and a yielding roller rotatable on the shaft and projecting beyond the rings and having its inner portions adjacent the pipe to compress against the pipe when the roller is distorted, the shaft having an end seated in a socket in one ring, 20 and extending into an opening through the other ring.

10. A bearing device for a string of drill pipe including, a cage adapted to be arranged 25 on the drill pipe, the cage including two spaced rings, and ribs connecting the rings, means for holding the cage against movement on the pipe, a shaft extending parallel to the drill pipe having one end seated in a 30 socket in one ring and having the other end extending into an opening through the other ring, a plug in the opening at the end of the shaft, and a yielding roller rotatable on the shaft and projecting outward beyond the 35 rings and having its inner portions adjacent the pipe to compress against the pipe when the roller is distorted.

11. A bearing device for a string of drill pipe including, a cage adapted to be arranged 40 on the drill pipe, the cage including two spaced rings, and ribs connecting the rings, means for holding the cage against movement on the pipe, said means including a plurality of grips seated in sockets in the rings and 45 having pointed ends projecting inward from the rings, and a plurality of circumferentially spaced yielding rollers rotatably mounted between the rings to rotate about axes parallel to the axis of the pipe, the rollers projecting outward beyond the cage to engage 50 the well walls and having their inner portions adjacent the pipe to compress against the pipe when the rollers are distorted.

12. A protective device for a string of pipe 55 or the like, operating in a well bore including a rigid cage adapted to surround the said string and including vertically spaced parts, means for holding the cage against movement on the string, and yielding members 60 mounted between the spaced parts and projecting outward beyond the cage to engage the well walls and having their inner portions normally spaced from the string and adapted to compress against the string when 65 the members are distorted.

13. A protective device for a string of pipe or the like operating in a well bore including a rigid cage adapted to surround the said string and including vertically spaced parts, 70 means for holding the cage against movement on the string, yielding members arranged between the spaced parts, tubular metal bushings carried by and extending longitudinally through the members, and pins extending through the bushings and extending between and carried by the said spaced parts, the members projecting outward beyond the cage to engage the well wall and having their inner portions adjacent the pipe 80 so as to compress against the pipe when the members are distorted.

In witness that we claim the foregoing we have hereunto subscribed our names this 15th day of March, 1930.

EDWARD CRAIG.
